UNITED STATES PATENT OFFICE.

FREDERICK WALTON, OF HEATHAM HOUSE, TWICKENHAM, COUNTY OF MIDDLESEX, ENGLAND.

MANUFACTURE, EMBOSSED, AND COLORING OF PANELS AND MOLDINGS, AND APPARATUS EMPLOYED IN SUCH MANUFACTURE.

SPECIFICATION forming part of Letters Patent No. 249,429, dated November 8, 1881.

Application filed July 26, 1881. (Model.) Patented in England May 27, 1880.

To all whom it may concern:

Be it known that I, FREDERICK WALTON, a subject of the Queen of Great Britain, residing at Heatham House, Twickenham, in the county of Middlesex, England, have invented certain new and useful Improvements in the Manufacture, Embossing, and Coloring of Panels and Moldings, and in Apparatus Employed in such Manufactures, (for which I have received 5 Letters Patent in England, No. 2,160, dated 27th May, 1880;) and I do hereby declare that the following is a full, clear, and exact description of the invention, which will enable others skilled in the art to which it appertains to make 10 and use the same.

The object of this invention is the printing of solid relief wall decoration, whether made of oxidized-oil compositions or others of a plastic nature. To insure perfect accuracy I employ a machine in which I both make the relief ornament and print it in a continuous operation; so I insure that a perfect register of the pattern is preserved between the raising of the relief and the imprint of color upon it. 20 To obtain this result I employ a cast-iron cylinder of about sixty inches diameter. Against this cylinder I run the embossing or relief-raising roller. I pass the foundation fabric on the face of the cylinder and feed the composition between it and the embossing-roller. The ornament in relief is thus produced. At the same time the fabric is secured to the cylinder, so that it may not shift, by being pressed at each edge onto small steel pins which project slightly 25 from the periphery of the cylinder. After the fabric has received its ornamental relief it travels some distance round the cylinder inside a casing, through which cold air is blown, the object being to cool the plastic composition and render it more fit to resist without loss of 30 form the pressure to which it is exposed while receiving the impression of the color-rollers. The coloring takes place almost immediately after the fabric has left the cooling-chamber. 35 The color-rollers are arranged round the circumference of the cylinder in the same manner as the rollers of a calico-printing or paper-staining machine. I use a flat printing-sur-

face, unless the pattern is in high relief and very irregular of surface; but when there is 50 considerable curvature of surface—as, for instance, in the cup-like form of a flower—I cut the wood or other printing-surface slightly to the form, but mainly I trust to the natural elasticity of the composition to yield to any slight 55 inequality. I prefer to use elastic inking or coloring rollers. I use the same machine in the production of tapestry-like hangings, the first or relief roller producing an indented surface in imitation of tapestry, and the color-rollers 60 printing suitable patterns on such rough or uneven surface. By printing on the raised surface the appearance of tapestry is produced. Sometimes I leave the relief ornaments without color and print only on the rough or uneven groundwork. After the printing of my 65 relief decoration by rollers I apply one or more revolving brushes, so as to distribute the color already put on, and to soften the outlines and tints and give that soft modulated shading 70 produced by hand-work. The action of the brushes should be coincident with the run of the material, and they should have also an intermittent movement to and from the fabric. It is necessary that these brushes should be 75 very lengthy, fine, and soft in texture, so as to enter freely all the inequalities of the surface. When the color is applied by means of flat blocks, flat brushes are similarly employed.

Figure 1 of the annexed drawings is a transverse section of a machine for the production in accordance with my invention and as described above. The backing fabric—preferably paper and woven fabric combined—is wound onto roller A, and passes from thence to a 80 break-roller, B, which is covered with wire card-cloth, to gripe the under side of the material. The roller B is provided with a loaded break-wheel, to regulate the strain put upon the fabric. The fabric then passes round the roller C 85 and under D, which spreads on a layer of composition. It then passes on to the embossing-roller E, which impresses or molds the pattern, and at the same time forces the fabric onto fine 90 steel pins which are placed round the periphery of the cylinder I.

F is a revolving steel knife, which cuts off the surplus edge of the fabric, and a doctor is provided to scrape off and arrest any composition at the edge, which might interfere with the subsequent printing operation. The fabric then passes into a covered chamber arranged around the cylinder, into which cool air is blown by means of a fan, for the purpose of cooling the heated composition, and thus rendering it sufficiently firm to enable it to take the impression of the printing-rollers G G G without distortion of form. The printing-rollers may be made of wood, metal, or a semi-elastic composition composed of solidified oil mixed with finely-ground cork, which will yield to the inequalities of surface.

G' G' G' are inking-rollers. For most purposes—such as the printing of low-relief or tapestry pattern—I prefer wood rollers cut in the usual way; but for high relief I use rollers cast or produced by electrotyping or similar process.

The brushes are shown at H H. They may be suspended on levers, and be actuated by a shaft slightly eccentric, or by other similar means.

The combined fabric described as employed, by preference, for the backing is made by uniting cloth and paper in a machine represented at Fig. 2. The cloth is put on roller A, the paper on roller B. They are united by being passed through rollers, the composition described below being fed in between, and the two combined are to be wound up at D.

To make the combining composition, I take of oxidized oil, sixteen hundred-weight; of New Zealand gum, two hundred-weight; of resin, four hundred-weight, three quarters, eighteen pounds. This composition or cement I call "No. 1." Of this No. 1 cement I take sixteen pounds; ocher, twenty pounds; red lead, one pound four ounces; paraffine-wax, one pound. This compound, which I call "No. 2," is mixed in a radial or other mixer, and a small quantity—say two pounds—of spirits of turpentine is added while mixing, to soften it slightly.

The composition for the face may be made as follows: I make a cement composed as follows: ninety-six pounds oxidized oil; eighteen pounds New Zealand gum; twenty-four pounds resin. Of this cement I take forty-eight pounds; wood fiber, forty-eight pounds; white lead, twelve pounds; wax and resin, four pounds; thick boiled oil, four pounds; bronze-green, one and one-fourth pound. This composition I call "No. 3."

In place of printing the fabric while it is still upon the roller which carries it when the raised pattern is produced, it may be conducted onto another roller by means of endless chains or bands furnished with pins to hold the fabric, so that it may not lose its form in passing from one supporting-surface to another. It is essential to my invention, however, that the fabric should be securely held in form from the time that the raised pattern is produced until

after it has been printed, and the better way is to retain the fabric throughout on the same supporting-surface. By another plan I make a sunken roller for each color, and I force a soft color composition into such sunken forms and clean the surface by means of a doctor. I then transfer the said composition onto a sheet of fabric prepared with my oil composition in an adhesive state, which takes the colored composition out of the hollows of the color-rollers.

Fig. 3 is a transverse section of a machine for the production of a raised-pattern fabric by the application to the face of a plane surface of molded pieces of colored composition, in the manner stated above. A is an engraved roller having a sunken pattern. B is a plain-surface roller, running at about the same or preferably higher surface-speed than A, so as to force the composition described below as No. 5 into the recesses of the roller. A doctor at C having a reciprocating motion across the roller cuts off the superfluous composition. A roll of compound fabric, as previously described, is fixed at D, and this fabric passes between rollers E and F, where it receives a layer of composition described as No. 4. This composition being slightly adhesive, when the fabric reaches the nip between rollers A and E, the composition in the sunken recesses of A is picked out and made to adhere to the plain surface, and as the two compositions are colored differently the effect is to produce the flat surface or groundwork of the design of a different color to the raised work.

The No. 4 or surface composition consists of forty-eight pounds oxidized oil; forty pounds wood fiber; twelve pounds white lead; one pound paraffine-wax; one pound resin; four pounds bronze-green.

The No. 5 or relief composition consists of forty-eight pounds oxidized oil; forty pounds wood fiber; six pounds white lead; six pounds hard boiled oil; two pounds resin; two pounds wax; two pounds Venetian red. Sufficient coal-naphtha or spirits of turpentine are added to make it about as soft as putty, and as much wax also is added as will allow it to stick to the composition on the surface, but not to adhere to the roller. After the fabric leaves this machine it is hung in a stove at about 100° Fahrenheit, to harden before use.

In some cases I take a backing of woven fabric combined with paper, and I print with oil-colors on the same in imitation of inlaid woods and the like. I indent the surface with fine lines or sunk work in any design by means of a pattern in relief on a brass or other roller. I print the same with surface blocks or rollers in several colors in the same machine, and when the color becomes set and partially dry I cut off the superfluous color by means of a doctor or knife-gage, leaving the color in the sunken design.

In order thus to produce work having the appearance of inlaid work, I take a roll of com-

ound fabric and place it in the machine represented at Fig. 4. A indicates the rolls. A plain roller at B spreads the composition before described as No. 4, while the roller C, which has a design in relief upon it, imprints the design as a sunken pattern into the surface of the composition. The fabric then passes through a cooling-chamber and to the printing-rollers D D, which deposit color into the sunken lines. The printing-rollers are such as are used for paper-staining, and are supplied with a good body of color, so as to more than fill the line-recesses. The fabric is afterward taken into a heated drying-room to partially harden, and when the color has become sufficiently hard and cheesy, so that it will not smear, the fabric is placed in a machine. (Shown at Fig. 5.) The fabric as taken from the drying-room is placed on a roll, A, and the end is passed under a roller, B, which is pressed against roller C by a spring behind the bearings. The fabric then passes between rollers C and D. A slight pressure is applied between rollers B and C and between rollers C and D, enough only to keep the fabric tight at E, where the doctor F works. This doctor has a very sharp edge, and is made to traverse the roller with a reciprocating motion of about five hundred strokes a minute. A little raw linseed-oil is applied at the point of cutting, to perfectly clean off the superfluous paint. The result is a pattern inlaid in the fabric.

In the production of embossed paper by machinery I make an embossing-roller of metal or other material, and I deposit color into the sunken part of such roller by means of elastic color-rollers. I then force into the sunken pattern a sheet of paper or paper coated or combined with solid oils or other materials by means of a counterpart roller or a roller of elastic material. By this means I emboss and print the paper or other fabric, as cloth, coated and stiffened with oil compounds, in the same machine.

Fig. 6 is a transverse section of a machine for simultaneously embossing and coloring paper or other fabric. The roll of paper or other fabric on which a layer of oxidized-oil composition has been spread is placed at A. The fabric passes from it round the roller B. C is a roller having the pattern sunk into it. The color is applied to the depressions in the roller C by means of the elastic color-rollers D and D, so that when the paper passes between B and C it is forced into the depressions in the engraved roller C and picks up the color. The paper or fabric then passes into a drying-room. The roller B may be a counterpart of C in metal, or it may be of slightly-elastic composition formed of solidified oil and wood fiber, made to adapt itself to the roller C by being run against it until a pattern is formed, as is well understood. I also take paper or other fabric, and I emboss the same between embossing-rollers, counterparts the one of the other, and as the paper passes on the roller having the raised pattern,

I print the same by rollers the surfaces of which are slightly elastic, to yield to the inequalities of surface.

The pattern or embossing rollers used in embossing or molding the faces of fabrics coated with oxidized-oil compositions and other fabrics require to be quickly and easily changed, and in order to do this I make the brass shells on which the pattern is cut in the form of rings, which slide onto a mandrel fitted with a key, to insure the right position of the ring being preserved. I can put several rings on one mandrel, so that I can produce a great variety of patterns. For instance, when I need a dado with two borders, one on each side, I can change and vary the borders in relation to the centers. I also vary the printing-cylinders in the same way. Figs. 7^a and 7^b represent embossing-rollers made with interchangeable rings assembled on a mandrel in this manner. Fig. 7^a shows a mandrel with loose shells adapted for making dados and the like with varying borders. Fig. 7^b shows a mandrel with loose shells, for rolling various widths of picture-moldings.

In the production of borders for picture-frames, furniture, and the like, which are very narrow, I put twenty to thirty on one roller, and the fabric so embossed is cut in the same machine into strips by means of circular knives fitted onto a shaft. The knives are kept apart by means of washers the exact width of the borders or moldings to be cut. In the same machine, also, I wind the moldings so cut onto small wooden bobbins, which are slid onto a revolving shaft. The bobbins are of the same width as the distance-pieces placed between the circular knives. These bobbins are so carried upon the shaft that they can slip as the shaft is made to revolve slightly in excess speed of the cutting-roller. This is requisite because, the moldings being of various thickness, slack would otherwise arise in some of the windings. When these moldings are wound each bobbin has a card-board or metal flange placed on each side of the bobbin, to protect it.

Fig. 8 represents the machine referred to above for making narrow borders. The compound fabric previously described, or stout paper, is wound on the roll A. B is a break-roller, covered with wire card, and weighted, to put an even strain on the cloth, which then passes between the rollers C C, to receive a layer of the composition. The compound fabric then passes to the embossing-roller D, which is composed of a series of concentric rings, as shown in Fig. 7^b. It then passes upward to two mandrels carrying circular knives, (marked E E.) The knives (of which there are as many pairs as there are widths of molding) are kept apart by means of little washers the width of the moldings, and thus the moldings are cut exactly. The moldings thus cut pass immediately onto a mandrel, which has also a number of these bobbins or washers the exact width of the moldings. These bobbins are slid loosely onto the mandrel and not keyed, and

they are tightened up by a screw at the end, having a rubber washer, to give spring-pressure. The mandrel is then driven by a slipping belt slightly in excess of the speed of the embossing-rollers, so that as the moldings vary in thickness the slip will roll up those that might otherwise get slack. There should be a distance of about five or six feet between the embossing-rollers and the cutting-knives, and the fabric should pass through a cooling-chamber, into which cold air is blown; otherwise the molded surfaces would be injured by the pressure in winding up. The strip of moldings may be rewound onto bobbins with flanges, for the purpose of storage and use. To fix this ornamental border onto wood moldings I use a machine in which the bobbin is placed on a spindle above a narrow traveling table adjustable to any angle. On this table I place the wood molding. The glue for fixing is placed on the molding by means of an elastic piece of rubber fitted to the form of the molding, and which spreads an even coat. The border is allowed to pass over this prepared surface, and is pressed onto it by an india-rubber or other elastic roller.

Fig. 9 represents the machine referred to above for putting the moldings onto the wood. A is the roll of molding. B is an iron roller. C is an iron roller with a rubber face, the face being molded to the form of the molding to be put on. The rubber faces can be changed for different forms of wood molding. D is an india-rubber wiper or gage to put on the thick glue used for fixing. Fig. 10 shows one method of using tubes for placing the moldings into position until set. To continue the pressure until the glue is set I place the moldings immediately after leaving the machine between boards having spaces of two or more inches between them. Into these spaces I insert long tubes of india-rubber, fastened at both ends, and I force water or air at suitable temperature into them. I prefer cold water to set the glue. The arrangement is represented in section at Fig. 10. A A are the boards; B B, the moldings, and C C the india-rubber tubes, to which cold water under some pressure is admitted. By another plan I continue the pressure by having an endless belt of india-rubber or other soft material to follow on the molding until the glue is set, so that the molding issues from the machine complete. This method is illustrated by Fig. 11. A A A are pressing-rollers. B B is an endless belt of india-rubber, about one inch thick; or I prefer an endless tube filled with water, which is more elastic, and which may be about three or four inches in diameter, according to the size of moldings manufactured. C is the india-rubber ductor to put on the glue.

In rolling or embossing, especially where fine lines are used, there is always great difficulty in preventing the material adhering to the rollers, and the difficulty is the greater if the rollers be warm. I have succeeded in over-

coming this by the use in the composition of a small quantity of paraffine-wax combined with soap, or alone. Most of the waxes have this quality; but I prefer paraffine-wax to any other. When using wax I can keep the embossing-roller at a high temperature, thus insuring a fine finish and perfect sharpness of the outlines. In using paraffine-wax I find about two per cent. of the whole weight of composition gives a good result; but it varies according to the more or less adhesiveness of the composition or the use the material is intended for. If beeswax is used, more is required, and Japan wax needs at least three times as much as paraffine, and then does not produce so good an effect.

I have found that castor-oil reduced into a semi-solid condition by the evaporation of its volatile constituents under heat can be used with great advantage, either alone or in combination with solidified linseed-oil and gum; and in some cases I use castor-oil in its natural state, combined with gum-kauri and solidified linseed-oil, the volatile constituents of the oil passing off during the combination under heat of the main materials.

I make a composition of castor-oil very suitable for panels in the following manner: I take twenty pounds of castor-oil and add to it forty pounds of kauri-gum chips, and boil them together in a caldron until thoroughly combined and the smell of the gum is evaporated. If I want a very hard composition, I mix this composition with about equal weight of fiber and coloring-matter, and then roll it into panels, and in proportion as I want the panels more pliable I add solidified linseed-oil to the composition when in the caldron or steam-heated pan.

For the manufacture of panels for the decoration of furniture or small surfaces I employ a set of three rollers of large diameter, say twenty-four to thirty inches. Two of these rollers are plain, and by them the composition is spread on the back fabric. The other of these large rollers carries the dies, (which are curved to the radius.) They are fixed so that they may be easily adjusted in position or removed. A number of these dies are fixed on the roller. Where, on account of the varying form and size of dies, there is a space, a blank form is put in. Fig. 12 represents this machine in section. In working this machine the fabric at A is passed between the rollers B and C and a layer of composition spread onto it. It is then passed forward to D. This roller is shown separately at Fig. 12^A. A number of dies suitable for door-panels, finger-plates, box-tops, and the like are placed upon the roller. They can be fixed either by sliding into grooves in the roller or they can be fastened by studs at the back of the die, as shown at Fig. 12^B. The shell of the roller is drilled full of holes at equal distances to receive the studs, and the studs are screwed to receive nuts at the back. Blank forms are put in in the same way, to fill

the spaces, when necessary. In another arrangement I have one large roller working by means of a rack motion in unison with a horizontal table, and the dies are fixed on such table in the same way as I fix them on the roller aforementioned, only that the dies do not need curving. I feed the material between the dies on the table and the roller which works over it, passing a cloth or fabric over the roller.

10 Fig. 13 represents a machine for working panels and like articles from flat dies. The panel-dies are placed on the table A A. The roller B and table A are made to travel in unison by means of a wheel on B working into a rack on each side of the table A A. The cloth is drawn from a roller at C, and the composition is placed, as shown, between the cloth and the dies on the table. The table can be steam-heated and the rolls driven by gears and steam-power. Several dies can be placed on the table in the same way as those fixed onto the cylinder in Fig. 12.

I apply to floor-cloths the method of embossing or otherwise producing on the surface of the fabric fine sunken lines wherever the printed pattern is to be placed. I then print with oil-color over the lined forms with superfluity of color, and when the color is set and dry I remove the superfluous color by means of a doctor. The paint is thus inlaid slightly beneath or even with the surface, producing fine effects and rendering the color durable. I prefer to print by a roller-machine. In place of engraved lines, a stippled surface may be produced deep enough to hold a body of color. In ornamenting floor-cloth in this manner I proceed as follows: I take a jute canvas, such as is usually employed, and I place it on the roller A of Fig. 4. The composition is spread between the rollers B and E, and then receives the design from roller C, which has the pattern in raised lines. The pattern is then printed on by the rollers D D, a superfluity of color being used. The cloth is next dried in a stove at a temperature of 100° Fahrenheit, and when sufficiently dry not to smear the color is taken off with a doctor, as described in respect to Fig. 5.

Having thus described the nature of my said invention and the manner of performing the same, I would have it understood that I claim—

1. The manufacture of an embossed and colored fabric by spreading a plastic composition upon a suitable backing material, embossing or raising a pattern in relief upon the plastic composition by means of a suitably-engraved roller, and then, while the compound fabric is still upon the surface which supported it when it was embossed, printing color onto the embossed surface by means of printing-rollers, so as to register accurately with the embossed or raised surface.

2. The manufacture of an embossed and colored fabric by spreading a plastic composition upon a suitable backing material, embossing or raising a pattern in relief upon the plastic composition by means of a suitably-engraved

roller, and then, in the same machine, and while the compound fabric continues to be held so that it cannot change its form, printing color onto the embossed surface by means of printing-rollers, so as to register accurately with the embossed or raised surface.

3. In the conduct of the process set forth in the first and second claiming clauses, causing the compound embossed fabric to be carried from the point where the raised pattern is produced by the action of the embossing-roller through a cooling-chamber, in which, by a current of air or other cooling means, the composition is cooled and hardened, to the printing roller or rollers, by which the color is applied to register accurately with the raised or embossed pattern.

4. The manufacture of an embossed and colored fabric by spreading a plastic composition upon a suitable backing material, and afterward producing a raised pattern in colors upon this compound fabric by applying to it colored composition by means of an engraved roller or rollers the hollows of which have been previously filled with such composition or compositions.

5. The manufacture of an ornamental fabric from a woven fabric and paper combined by a suitable composition, with which also the paper is surfaced, by producing thereon an indented pattern, applying colored composition over it, and finally removing the surplus composition, so as to leave the color only in the lines of the pattern.

6. The means of simultaneously embossing and coloring paper or other fabrics on which a layer of oxidized-oil composition has been previously spread by the use of an embossing-roller the sunken pattern of which is colored by means of elastic color-rollers, and into the hollows of which embossing-roller so colored the paper is afterward forced.

7. The method of embossing and printing paper, consisting in passing paper between a pair of embossing-rollers, and while the embossed paper still remains on the roller on which is the raised pattern applying color to the raised parts only of the paper by means of elastic color-rollers.

8. The combination of the roller upon which the fabric is wound, the break-roller, the rollers by which the fabric is coated with a layer of composition, the embossing-roller, the mandrels carrying the circular knives, and means for cooling the coated fabric, substantially as and for the purpose hereinbefore set forth.

9. The combination, with the mechanism by which the fabric is supplied, coated, embossed, cut, and cooled, of the printing-rollers, substantially as described.

10. The combination, substantially as hereinbefore set forth, of the roll upon which the prepared molding or ornamental border is wound, the mechanism for supplying the wood molding and applying glue thereto, and the elastic molded face pressure-rolls, whereby

the border is caused to adhere to the wood, as described.

11. The use in the manufacture of coated fabrics of a composition consisting of castor-oil reduced by evaporation to a semi-solid condition and mixed with other ingredients, substantially as described.

12. The method of ornamenting floor-cloth by producing thereon an indented pattern, ap-

plying colored composition over it, and finally removing the surplus composition, so as to leave the color only in the lines of the pattern.
